UNITED STATES PATENT OFFICE.

WILLIAM J. KELLY, OF READING, PENNSYLVANIA, ASSIGNOR TO UNITED SHOE MACHINERY COMPANY, OF PATERSON, NEW JERSEY, A CORPORATION OF NEW JERSEY.

PROCESS OF MAKING SHOES.

1,214,316.

Specification of Letters Patent. Patented Jan. 30, 1917.

Application filed April 6, 1915. Serial No. 19,490.

To all whom it may concern:

Be it known that I, WILLIAM J. KELLY, a citizen of the United States, residing at Reading, in the county of Berks and State of Pennsylvania, have invented certain Improvements in Processes of Making Shoes, of which the following description, in connection with the accompanying drawings, is a specification, like reference characters on the drawings indicating like parts in the several figures.

This invention relates to processes of making shoes and particularly to lasting processes.

15 An object of the invention is to secure an improved lasting result in the lasting step of shoe manufacture. The process is herein shown as carried out in the manufacture of stitch-down shoes, but it will be understood 20 that the invention is not restricted to the illustrated use and that in so far as it may be utilized in the manufacture of other types of shoes such use of the process is intended to be included within the scope of the protection claimed.

In the lasting of shoes it is desirable that the upper be stretched considerably and that it be fitted closely to the last, and to insure a satisfactory lasting result it is necessary 30 that the fastenings used to secure the upper in lasted position are effective for this purpose. In the lasting of stitch-down shoes and also of welt shoes it is both desirable and requisite that the fastenings not only 35 shall securely hold the upper in lasted position but that they shall be so located and of such dimensions that they will not interfere with the succeeding operations on the shoe, particularly the sole attaching operation.

40 It has been found that the most effective individual fastening for use in lasting stitch-down shoes is the staple, such use of the staple in a practical process of lasting stitch-downs by which the upper is secured exactly 45 in lasted position being first disclosed in United States Letters Patent No. 1,117,086, granted November 10, 1914, on an application of Adam H. Prenzel, and staples have many advantages for fastening an upper in 50 lasted position in the manufacture of welted footwear, as set forth in United States Let-

ters Patent No. 1,163,596, granted December 7, 1915, on an application of James Cavanagh. In carrying out the processes disclosed in said Letters Patent it is customary to use 55 a staple of comparatively fine wire and to drive this staple tightly down into the angle of the upper, and in lasting shoes of ordinary construction the lasting result obtained by the use of this staple alone is very satisfactory. When lasting unusually stiff leather, like patent leather, or when lasting leather which is not strong enough to be secured against the lasting strain by ordinary fastening means, difficulty is sometimes experienced, particularly about the toe portion 60 of the last in securing the desired lasting result, for example, due to the tendency of the fastenings to pull through the upper.

A further object of the invention is a process 70 of lasting which will facilitate the shaping of the upper to the last and the securing of the upper exactly in lasted position.

In carrying out the process of this invention the machine shown in my co-pending 75 application Serial No. 18,540 filed April 1, 1915, may conveniently be used, and in the accompanying drawings, illustrating the process, Figure 1 shows in perspective a portion of a shoe lasted in accordance with the 80 process; and Fig. 2 shows sufficient of the machine of my co-pending application to illustrate the manner of carrying out the process.

In practising the process, the preferred 85 procedure is to assemble upon the last an upper 2 and a middle sole or slip sole 4 which extends somewhat beyond the edge of the last. The parts being assembled upon the last, the operator wipes the upper down 90 the side of the last and forces the angle of the upper into the angle between the last and the sole margin, and then inserts a staple 6 substantially in the vertex of the upper angle, this staple being so driven that 95 it will pass through the slip sole and will have its ends clenched upon the bottom face of the slip sole.

The operator usually begins the lasting operation by stretching the upper over the 100 last at each end of the tip seam 8, locating the tip seam carefully, and then securing

the upper to the last upon each side near or at the tip seam. He then proceeds in either direction from the tip seam, usually lasting back toward the shank first and then about 5 the toe end of the upper.

When the operator experiences difficulty in securing the upper tightly in lasted position by means of the staples alone, or when he desires to secure the upper more effectively and permanently in lasted position, he causes a cord 10 or similar means to be forced into the angle of the upper and into the angle between the last and the sole margin at the same time that the wiping and stretching of the upper over the side of the last is effected, the cord being preferably led over the end of the lasting tool so that said tool carries the cord into said angle. Moreover, as more fully described in my co-pending 10 application hereinabove identified, the cord is preferably so located with respect to the staple guiding means, or with respect to the staple guide in said lasting tool, that the staple will secure the cord, whereby the cord 15 acts both as auxiliary upper securing means and as means for preventing the staples from pulling through the upper.

In Fig. 2 of the drawings, the lasting tool 193 of my co-pending application is shown partly in section to illustrate the manner of 20 locating the cord and staple, the cord being led from a spool 212 having a take-up connection with a frictionally retarded shaft 224, more fully described in my co-pending 25 application, over a guide wheel 214 and through the loop 216 of a second take-up 218 adjacent to the lasting tool, said last-mentioned take-up, as more fully described in my co-pending application, serving to 30 control the cord and prevent its looping during the upper wiping and stretching operations.

Having fully described my invention, what I claim as new and desire to secure by 35 Letters Patent of the United States is:

1. That improvement in the art of making shoes which consists in assembling upon a last an upper and a sole, effecting a step-by-step lasting operation by successively engaging said upper by a lasting tool, over the 40 upper engaging surface of which a cord is laid, and forcing said upper into lasted position upon said sole, at the same time forcing said cord into upper securing position, and then inserting a fastening to secure said 45 cord and said upper in the position to which they have been brought during said stretching operation.

2. That improvement in the art of making 50 shoes which consists in assembling upon a last an upper and a sole, effecting a step-by-step lasting operation by successively engaging said upper by means of a lasting tool, over the upper engaging end of which

a cord is laid, and stretching said upper 55 over the last into lasted position upon said sole, whereby said cord is brought into upper securing position simultaneously with the upper stretching operation, and then 60 permanently securing said upper in lasted position by a staple inserted through said upper into said sole in position to hold said cord.

3. That improvement in the art of making 65 shoes which consists in assembling upon a last an upper and a sole, wiping the upper down the side of the last, and forcing the angle of the upper into the angle between the last and the sole margin, forcing a cord into said angle simultaneously with the wiping 70 of the upper and the forcing of the upper into the said angle, and then inserting a fastening to secure the upper and said cord.

4. That improvement in the art of making 75 shoes which consists in assembling an upper and a sole upon a last, effecting in a step-by-step manner the stretching of the upper over the last and the forcing of the angle of the upper into lasted relation to the sole, inserting a fastening in said angle 80 to secure the upper in lasted position, and during the stretching of the upper and the forcing of the angle of the upper into lasted relation to the sole forcing into said angle auxiliary fastening means into position to 85 coöperate with said first-mentioned fastening means.

5. That improvement in the art of making 90 shoes which consists in assembling an upper and a sole upon a last, turning out the 95 margin of the upper, engaging said upper by means of a lasting tool, wiping it down the side of the last and forcing the angle of the upper into the angle between the last and the sole margin, and leading a cord across 100 the end of said lasting tool before said wiping and stretching operations in such relation to said tool that said cord is forced into 105 said angle simultaneously with the wiping of the upper and the forcing of the angle of the upper into the angle between the last and the sole margin, then securing the upper in lasted position by fastening means inserted in said angle in position to secure 110 said cord in said angle.

6. That improvement in the art of making 115 shoes which consists in assembling upon a last an upper and a sole, effecting a step-by-step lasting operation by manipulations of the upper including forcing successive portions of the upper into lasted relation to the sole, forcing a cord into upper securing position by a tool over the upper engaging end of which the cord is laid, and inserting an upper securing fastening in such relation to 120 the cord as to prevent the head of the fastening from pulling through the upper.

7. That improvement in the art of making

shoes which consists in assembling upon a last an upper and a sole, effecting a step-by-step lasting operation by forcing successive portions of the angle of the upper into lasted relation to the sole, at the same time forcing a cord into upper securing position in said angle by a tool over the upper en-

gaging surface of which the cord is laid, and then fastening said cord by an upper securing fastening.

10

In testimony whereof I have signed my name to this specification.

WILLIAM J. KELLY.
